UNITED STATES PATENT OFFICE.

JOHN MEIGGS EWEN, OF CHICAGO, ILLINOIS, ASSIGNOR TO THE LUXFER PRISM PATENTS COMPANY, OF SAME PLACE.

DESIGN FOR A PRISM PAVEMENT-PANEL.

SPECIFICATION forming part of Design No. 28,019, dated December 7, 1897.

Application filed October 2, 1897. Serial No. 653,861. Term of patent 14 years.

To all whom it may concern:

Be it known that I, JOHN MEIGGS EWEN, a citizen of the United States, residing at Chicago, in the county of Cook and State of Illinois, have invented a new and original Design 5 for Prism Pavement-Panels, of which the following is a specification.

My invention relates to a new and original design for prism pavement-panels and is illustrated in the accompanying drawings, where-
10 in—

Figure 1 shows a plan view of a prism pavement-panel embodying my design. Fig. 2 is a section therethrough on line 2 2.

15 A A are surface areas with rounded corners; B B, intermediate surfaces between

such surface areas; C C, prisms on the opposite side of the panel.

The essential features of my design are found in a prism pavement-panel having on 20 one side a series of prisms and on the other side a series of oblong surfaces with rounded corners arranged in regular rows, with intermediate surfaces between their several edges.

25 I claim—

A design for a prism pavement-panel, substantially as shown and described.

JOHN MEIGGS EWEN.
